(57) **CLAIM**

The ornamental design for a hydraulic cylinder, as shown and described.

DESCRIPTION

FIG. 1 is a front, top, right, perspective view of a hydraulic cylinder in accordance the present design;

FIG. 2 is a front elevation view thereof;

FIG. 3 is a rear elevation view thereof;

FIG. 4 is a left-side elevation view thereof;

FIG. 5 is a right-side elevation view thereof;

FIG. 6 is a top plan view thereof;

FIG. 7 is a bottom plan view thereof;

FIG. 8 is a partial cross-sectional front, top, right perspective view thereof;

FIG. 9 is an enlarged partial cross-sectional front, top right perspective view thereof;

FIG. 10 is a partial cross-sectional front elevation view thereof; and,

FIG. 11 is an enlarged partial cross-sectional front elevation view thereof.

The broken lines of even length shown in the drawings illustrate portions that form no part of the claimed design.

(Continued)

The broken lines of uneven length (dash-dot-dash) indicate enlargements of the claimed design (FIGS. 8-11).
